UNITED STATES PATENT OFFICE.

WILLIAM F. SHAW, OF PUEBLO, COLORADO.

ARTIFICIAL-TOOTH ANCHOR.

1,158,732.

Specification of Letters Patent.

Patented Nov. 2, 1915.

Application filed March 24, 1915. Serial No. 16,659.

To all whom it may concern:

Be it known that I, WILLIAM F. SHAW, a citizen of the United States, residing at Pueblo, in the county of Pueblo and State of Colorado, have invented a new and useful 5 Artificial-Tooth Anchor, of which the following is a specification.

The present invention appertains to dental bridge-work, and aims to provide a novel 10 and improved device for anchoring an artificial tooth or bridge to a natural tooth.

It is the object of the invention to provide an anchor for dental bridge-work or an 15 artificial tooth which will not require the excessive grinding away of the natural tooth, which will be invisible so as not to cover or encumber the natural tooth, which can be securely fastened to the natural tooth, and which will be both simple and inexpensive 20 in construction, and simple, practical and efficient in its application to the natural tooth.

With the foregoing and other objects in view which will appear as the description proceeds, the invention resides in the combination and arrangement of parts and in the 25 details of construction hereinafter described and claimed, it being understood that changes in the precise embodiment of the invention herein disclosed can be made within 30 the scope of what is claimed without departing from the spirit of the invention.

The invention is illustrated in its preferred embodiment in the accompanying drawing, wherein:—

Figure 1 is a perspective view of the improved anchor. Fig. 2 is a sectional view of a pair of teeth illustrating the device employed for anchoring an artificial tooth to a natural tooth. Fig. 3 is a plan view illustrating a pair of the anchors employed for supporting a bridge for a plurality of artificial teeth arranged between a pair of natural teeth.

In carrying out the invention, the anchor 45 is formed from a plate or strip of gold or other sheet metal, the plate or strip being doubled to provide a two-ply web 2, having a loop 3 at one end, and the angularly extending or bent portions 4 at its other end. 50 The loop 3 constitutes the intermediate portion of the plate or strip, and the portions 4 constitute the end portions of the plate. The portions 4 are flush, and provide an abutment to which an artificial tooth or 55 bridge may be cemented or otherwise secured. The loop or member 3 is relatively

short, and the web 2 preferably increases in width from the loop 3 to the abutment portions 4, and the portions 4 preferably project beyond the web 2.

The anchor embodies a second element 60 which is in the form of a pin or post 5 having one end secured within the loop 3, and having its other end pointed, if desired, and projecting from the loop 3 in the same direction that the abutment portions 4 project from the web 2. The pin or post 5 may be welded, soldered or otherwise secured within the loop 3.

In applying the anchor to a natural tooth, 70 reference being had to Fig. 2, the natural tooth 7 is provided with an approximately central bore 6 for the reception of the pin or standard 5 and loop 3, and a slot 8 is 75 cut or formed in the tooth between the bore 6 and one side of the tooth. The bore 6 and slot 8 are properly formed for receiving the pin 5 and web 2, respectively, whereby the anchor will be embedded firmly within the natural tooth, with the abutment portions 80 4 resting snugly against the respective side of the tooth. The web 2 in fitting within the slot or kerf and the pin 5 or loop or portion 3 fitting within the bore 6, will securely fasten the anchor within the natural 85 tooth, and the anchor may be cemented or otherwise secured within the tooth to prevent the anchor from slipping out of engagement with the tooth. The artificial 90 tooth 9 which lies at one side of the natural tooth 7 is soldered, cemented or otherwise fastened to the abutment portions 4, so that the artificial tooth will be carried firmly by the natural tooth.

A pair of the anchors may be employed, 95 as illustrated in Fig. 3, for supporting a bridge, each of the two anchors being applied to the respective natural tooth 7' in the manner that the single anchor is applied to the natural tooth 7 as above described. 100 The teeth 7' are provided with bores 6' for receiving the pins 5 and loops 3 of the two anchors, and the said teeth are also provided with slots 8' for receiving the webs 2. The bridge 10' is firmly soldered or otherwise secured to the abutment portions 4, and the 105 artificial teeth 9' are fastened in any suitable manner to the bridge 10' to be supported between the natural teeth 7'. In this use of the anchors, the abutment portions 4 110 as well as the bridge will lie at the lingual sides of the teeth, so that neither the anchors

or bridge will be exposed to view. In the use of the anchor as illustrated in Fig. 2, the abutment portions 4 will lie between the two teeth, and thus be concealed from view.

5 The present anchor is of advantage for numerous reasons, which will be obvious to the dentist. The anchor may be used for supporting one or more teeth, and requires a minimum amount of drilling or grinding 10 of the natural tooth or teeth. Ordinarily, crowns are employed upon the natural teeth, and this requires considerable grinding away of the teeth upon the exterior thereof, which is objectionable. The crowns are also 15 objectionable since they are exposed to view, whereas in the present case, the anchors or attaching members are hidden from view so that the teeth will be unencumbered at their forward or outer sides. The present 20 anchor is simple and inexpensive in con-

struction, but at the same time, is thoroughly practical and efficient in use. The anchors may be quickly and easily applied to the teeth, and without great cost, or rather, with a minimum expense.

25

Having thus described the invention, what is claimed as new is:

A dental anchor comprising a web adapted to fit in a slot in a tooth and having an abutment portion at one end, and a pin attached to the other end of the web and projecting from the web to fit within a bore in the tooth.

In testimony that I claim the foregoing as my own, I have hereto affixed my signature in the presence of two witnesses.

WILLIAM F. SHAW.
